TRANSMISSION CIRCUITS

Application filed September 28, 1927. Serial No. 222,438.

This invention relates to transmission circuits and particularly to such circuits in which amplifying devices are employed.

An object of the invention is to improve the amplification-frequency characteristics of an amplifying circuit.

A further object is to extend the range of signaling frequencies which may be amplified without appreciable distortion by an amplifying circuit for a given amount of amplification therein.

A further object is to increase the voltage amplification which may be obtained in an amplifier circuit for a given range of frequencies transmitted and a given standard of quality of transmission.

A feature of the invention is a multi-stage vacuum tube amplifier circuit having a tuned input circuit, the tuning of which is automatically controlled in accordance with the frequency of incoming waves.

The above objects are accomplished in a multi-stage vacuum tube amplifier circuit including an input transformer and an interstage transformer by designing the interstage transformer to work on the leakage resonance point of its impedance characteristic for the maximum frequency at which voltage amplification is desired in the input transformer.

More specifically stated, the invention comprises an amplifier circuit consisting in part of an input transformer, a space discharge device, an interstage transformer and a second space discharge device connected in cascade, the interstage transformer having leakage inductance of such value as to resonate with the distributed capacity between its windings and the effective capacity of the vacuum tube into which it feeds at a frequency near the upper end of the band of signaling frequencies to be amplified by the input transformer. The interstage transformer will present a low impedance to the plate circuit of the preceding tube at the resonant frequency and a high impedance thereto at lower frequencies. This results in a decrease in the effective input capacity, and therefore, an increase in the input impedance of the preceding tube, as the frequencies to be transmitted approach the resonant frequency. This in-

crease in the tube input impedance at the high frequencies results in an increase in the voltage amplification which may be obtained in the input transformer at the high end of the frequency band and thus permits the input transformer, and therefore the amplifier circuit as a whole, to transmit a wider frequency band without appreciable distortion for a given voltage amplification, or the same frequency band with a greater voltage amplification.

The invention will be better understood by reference to the following detailed description when read in connection with the accompanying drawing in which Fig. 1 shows schematically a multi-stage vacuum tube amplifier circuit embodying the invention; Fig. 2 is a schematic showing of a simplified circuit equivalent to the circuit of Fig. 1; Fig. 3 shows graphically the transmission and impedance characteristics of a transformer such as is used as the interstage transformer in the circuit of Figs. 1 and 2; Fig. 4 shows schematically a vacuum tube amplifier circuit embodying a modification of the invention; and Fig. 5 shows graphically the impedance and transmission characteristics of a portion of the circuit of Fig. 4.

In Fig. 1, a multi-stage amplifier circuit is shown connected between an incoming line 1 and an outgoing line 2 for impressing on the outgoing line in amplified form signals received over the incoming line from a source 3. The amplifier circuit comprises an input transformer 4 having a primary winding 5 and a secondary winding 6, a three-electrode vacuum tube amplifying device 7, an interstage transformer 8 having a primary winding 9 and a secondary winding 10, a second three-electrode vacuum tube amplifying device 11 and an output transformer 12 having a primary winding 13 and a secondary winding 14, connected in cascade in the order given. The incoming line 1, the impedance of which is represented by the resistance 15, is connected across the primary winding 5 of input transformer 4, and the outgoing line 2, the impedance of which is represented by the resistance 16, is connected across the secondary winding 14 of the output transformer 12, 100

The space discharge amplifying devices 7 and 11 have the usual filament heating, space current supply and grid polarizing batteries.

To obtain the maximum width for the band of signaling frequencies which may be transmitted without distortion by the amplifier circuit described for a given amount of amplification, or the maximum amplification for a given band width and a given standard of quality of transmission, in accordance with the invention, the interstage transformer 8 and the input transformer 4 are designed in the manner explained below in connection with Figs. 2 and 3 of the drawing.

In Fig. 2 is shown a simplified circuit equivalent to the amplifier circuit of Fig. 1 in which, in the usual manner, each of the transformers 4, 8, and 12, is represented by a T network, the series inductance arms of which represent the leakage inductance of the transformer, and the shunt inductance arm its mutual inductance, and in which each of the amplifying tubes 5 and 6 with its input and output impedances is represented by a network, shown in a dotted box correspondingly marked, comprising a source of electro-motive force e_1 or e_2 , a shunt resistance R , and shunt and series capacities C_1 and C_2 , C_1 being the grid-filament capacity of the tube and C_2 the effective grid-plate capacity of the tube.

As pointed out in the patent to W. L. Casper 1,530,649, issued March 24, 1925, a transformer having leakage inductance, as represented by the series inductance arm of the T networks in the simplified circuit of Fig. 2, when working into a vacuum tube consisting chiefly of capacitive impedance, has impedance-frequency characteristics such as shown in Fig. 3 of the drawing.

As shown in Fig. 3, the impedance characteristic of such a transformer when viewed from its primary winding terminals, as indicated by Z_3 in Figs. 1 and 2, has a resistance component, as indicated by the curve R , and a reactance component as indicated by the curve X . The reactance component X of the impedance characteristic has a parallel resonant portion and a series resonant portion. At the frequency indicated by the point H on the curve X , the transformer passes through parallel resonance, and at the frequency indicated by the point E on the curve X , the transformer passes through series resonance. If the leakage inductance of such a transformer, the distributed capacity of its windings and the capacity of the vacuum tube into which it works are properly proportioned, the voltage amplification-frequency characteristic of this transformer circuit will be flat over a wide range of frequencies, as shown by the curve A of Fig. 3, but a flat characteristic is not essential to the at-

tainment of the results described in this invention.

A transformer of the type just described is employed as the interstage transformer 8 in the circuit of Fig. 1, the transformer 12 in the circuit of Fig. 1 being an ordinary output transformer designed to connect the output of tube 11 to the load impedance represented by the resistance 16. It is desired to obtain as high a voltage amplification as possible for the input transformer 4. If input transformer 4 is designed to have minimum distributed capacity between its windings, it may be shown as follows that the amount of voltage amplification which may be obtained therein is limited by the impedance looking from transformer 4 into the input circuit of tube 7, and the value of this impedance is limited by the input capacity of tube 7.

If the input transformer 4 is assumed to be working on the parallel resonance point of its impedance characteristic, the maximum voltage amplification ratio obtainable thereby is when the impedance of the incoming line which we may designate Z_1 , as represented by the resistance 15 in the circuits of Figs. 1 and 2 of the drawing, times the impedance ratio R of input transformer 4, is equal to the anti-resonance impedance, which we may designate Z_2 , of the secondary winding 6 of this transformer with its distributed capacity and the input capacity of the tube 7 into which it works,

$$Z_1 R = Z_2 \quad (1)$$

and

$$Z_2 = \frac{Q}{2\pi f C} \quad (2)$$

where f is the desired frequency to be transmitted on the center of the desired frequency range, C the tube capacity plus the transformer capacity, and Q the ratio of the reactance to the resistance of the secondary winding of the transformer at the anti-resonant frequency.

The voltage amplification under these conditions equals $\frac{\sqrt{R}}{2}$, where R is the impedance ratio, or $\sqrt{R}$ the turns ratio of the transformer.

The input impedance Z_2 is therefore limited by the capacity C since the coil secondary inductance can be changed by design to resonate with the capacity present. As C is decreased, Z_2 is increased which has the effect of increasing the available voltage step-up of transformer 4.

Similarly, when the transformer 4 is working on the leakage resonance point of its impedance characteristic, which usually occurs at its upper limiting frequency, the voltage amplification of the transformer is given by the following relation.

$$\text{Voltage amplification} = \frac{1}{2\pi f C Z_1 \sqrt{R}} \quad (3)$$

where the voltage amplification is the ratio of the voltage on the grid of tube 7 to the E. M. F. of the source 3, and R is the impedance ratio of transformer 4. Now if C is decreased, it follows that the voltage amplification of transformer 4 is increased. Since the capacitive impedance of the tube and transformer increases as the frequency diminishes it is in general possible to maintain the same voltage amplification at lower frequencies as occurs at the upper limiting frequency and to obtain a substantially flat characteristic over a wide band of frequencies.

Now, it is well known that if a three-electrode vacuum tube amplifying device is short-circuited in its output side, its input capacity is a minimum, since it is composed of grid-filament capacity and effective grid-plate capacity in parallel.

$$C = C_{gf} + C_{gp}(1 + \mu_e) \quad (4)$$

and in such a case, the effective amplification factor μ_e of the tube is zero. On the other hand, it is also well known that if the plate circuit of a three-electrode vacuum tube is open circuited or terminated in a high impedance, the input capacity of the tube is greatly increased, since the effective amplification

$$\mu_e = \frac{Z_3}{\mu_o Z_3 + R_p} \quad (5)$$

where Z_3 is the terminating impedance, R_p internal plate impedance and μ_o is the characteristic or inherent amplification factor of the tube.

With a given amount of apparatus, it is desirable to obtain a maximum voltage amplification with a minimum amount of variation in the amplification over a wide range of frequencies. As shown in the above discussion, this may be accomplished by making the input capacity of tube 7 a minimum at the highest frequencies to be transmitted. By designing the interstage transformer 8 so that it passes through leakage resonance at a frequency near the upper end of the band to be transmitted by the input transformer 4, the impedance of the interstage transformer will be a minimum at this frequency, and will increase for the lower frequencies, as shown by the curves of Fig. 3. The plate circuit of tube 7 is, therefore, effectively short-circuited for currents of the resonance frequency, but is terminated at other lower frequencies by an impedance which decreases as the frequency increases. As brought out above, this causes the input capacity of tube 7 to decrease with increasing frequency, making its input impedance more nearly constant instead of varying inversely with frequency. This decrease

in capacity extends the width of the frequency band which may be transmitted by the input transformer 4 with a given gain variation and thus the width of band transmitted by the amplifier circuit as a whole.

In an actual comparison of the results obtainable with the circuit of the invention with those obtainable with a similar amplifier circuit but using resistance interstage coupling instead of transformer coupling, it was found that the band width transmitted by the input transformer with variation of 1 TU or less is increased about 15 per cent by using an interstage transformer in place of a resistance interstage coupling and by utilizing the effect of leakage resonance of the interstage transformer on the input capacity of the first tube.

The circuit of the invention may also be used for improving the impedance characteristic of the amplifier when viewed from the primary winding of transformer 4. An input transformer designed to give a uniform impedance characteristic usually operates at the shunt resonance point of its characteristic with a resistance bridged across the primary terminals. As long as the coil impedance is high compared to this resistance, the effective impedance across these terminals will be substantially the resistance of the shunt. In the copending application of F. E. Field, Serial No. 98,758, filed March 31, 1926, there is disclosed a transformer so designed that its inductance will decrease with increasing frequencies due to the screening effect on the flux of the eddy currents produced in the laminations of its core, thus approaching a condition of continuous parallel resonance, i. e. a resonance point which is automatically adjusted in accordance with the frequency with the distributed capacity of the transformer windings and the input capacity of the vacuum tube into which it works. Fig. 4 shows a multi-stage amplifier circuit employing an input transformer 4' having a resistance 17 bridged across its primary winding and an interstage transformer 8 equivalent to that described in connection with the circuit of Fig. 1. As the effect of the interstage transformer 8 is to cause the input capacity of the vacuum tube 7 to decrease with increasing frequency due to leakage resonance, indicated by the dotted variable capacity across the input terminals of tube 7, and the effect of the input transformer is to cause the inductance effectively in shunt with the input circuit of tube 7 to decrease with increasing frequency, as indicated by the dotted variable inductance across the input terminals of tube 7; the effects produced by the input transformer 4' and the interstage transformer 8 may be combined to more nearly approximate the condition of continuous resonance for the input transformer. This results in a very material improvement in the impedance characteristic of the input trans-

former, since its impedance will remain very high compared to the shunt over a wider frequency range.

The improvement in impedance and amplification characteristics of the input transformer in the circuit of Fig. 4 due to the action of interstage transformer 8 is shown in the curves of Fig. 5. In the upper part of Fig. 5, the solid curves r and X represent respectively the resistance component and reactance component of the impedance characteristic for the input transformer taken alone over a frequency range extending from a frequency f_1 to a frequency f_2 , the latter frequency being the frequency at which the interstage transformer passes through series resonance, and the dotted portions of the curves r and X indicate the change in the impedance characteristic due to the action of the interstage transformer 8 in the circuit. In the lower part of Fig. 5 the solid curve A is the amplification characteristic of the input transformer alone over the same frequency range, and the dotted portion of the curve indicates the improvement in the amplification characteristic of the input transformer due to the action of the interstage transformer 8 in the circuit.

It is to be understood that this invention is not limited to the particular form described above, but that it may be variously modified without departing from the spirit of this invention as defined in the appended claims.

35 What is claimed is:

1. In an electric discharge amplifier having an input circuit and an output circuit, means in said output circuit for making the capacity of said input circuit a minimum at substantially the upper limit of a wide band of frequencies to be amplified.

2. In an electric discharge amplifier having an input circuit and an output circuit, for amplifying waves comprising a band of frequencies, means in said output circuit for making the capacity of said input circuit a minimum for at least a part of the frequency band to be transmitted.

3. In an electric discharge amplifier having an input circuit and an output circuit, means in said output circuit for making the impedance of said input circuit a maximum at the upper limit of a wide band of frequencies to be amplified.

55 4. In an electric discharge amplifier having an input circuit and an output circuit, said input circuit comprising an input transformer having a primary winding and a secondary winding, means in said output circuit for making the capacity of said input circuit effectively in shunt to said secondary winding a minimum for a frequency near the upper limit of a wide band of frequencies impressed on said input transformer.

65 5. In a circuit for amplifying waves com-

prising a wide band of frequencies, an input transformer supplied with said waves, a space discharge device fed thereby, and an output circuit fed by said space discharge device, means in said output circuit for making the input impedance of said space discharge device a maximum for a frequency near the upper limit of the band to be amplified. 70

6. In a circuit for amplifying waves comprising a wide band of frequencies, an input transformer supplied with said waves, a space discharge device fed by said transformer, an output circuit fed by said space discharge device and means in said output circuit for making the input capacity of said space discharge device a minimum at a frequency near the upper limit of the band to be amplified. 75 80

7. In combination, in a circuit for amplifying waves comprising a wide band of frequencies, an input transformer, a space discharge device having an input circuit fed thereby, and means automatically responsive to change in the frequencies to be amplified for controlling the impedance of said input circuit so that said input transformer will produce on said waves a maximum amplification for a given width of said band and a given amount of distortion therein. 85 90

8. In combination in a circuit for amplifying waves comprising a wide band of frequencies, an input transformer, a space discharge device having an output circuit, and an input circuit offering substantially a capacitive impedance to waves transmitted by said transformer, and means in said output circuit automatically responsive to variations in the frequency of said waves impressed on said input transformer to control said capacitive impedance so that it is a maximum for the highest frequency in the band to be amplified and remains substantially the same at somewhat lower frequencies in said band. 95 100 105

9. In a circuit for amplifying waves comprising a wide band of frequencies, an input transformer supplied with said waves, a space discharge device having an input circuit and an output circuit, said input circuit being fed by said transformer, a second transformer fed by said space discharge device, said second transformer being such as to offer minimum impedance in said output circuit to currents of a frequency near the upper limit of the band to be amplified, and a higher impedance therein to currents of the lower frequencies in said band. 110 115

10. In a circuit for amplifying waves comprising a wide band of frequencies, an input transformer supplied with said waves, a space discharge device having an input circuit and an output circuit, said input circuit being fed by said input transformer, a second transformer fed from said output circuit, said second transformer feeding into a load circuit having a substantially capacitive impedance, said second transformer being designed 120 125 130

with respect to said space discharge device and said load circuit to control the output impedance of said input transformer so as to effectively increase the width of the frequency band which may be transmitted thereby for a given amount of amplification and a given amount of distortion.

11. In a system for amplifying electrical waves comprising a wide band of frequencies, a circuit comprising an input transformer having a primary winding supplied with said waves and a secondary winding, a space discharge device having an input circuit connected to said secondary winding, and an output circuit, a circuit having a substantially capacitive impedance, a second transformer coupling the last-mentioned circuit to said output circuit, said second transformer offering a low impedance to currents in said output circuit of a frequency near the upper end of said band and a higher impedance to currents therein of the lower frequencies in said band, whereby the capacity of said input circuit looking from said input transformer is a minimum for transmitted waves of said frequency and increases for transmitted waves of the lower frequencies in said band.

12. In combination, a source of waves comprising a wide band of frequencies, and a circuit for amplifying said waves comprising an input transformer having a primary winding and a secondary winding, said primary winding being connected to said source, a space discharge device having an input circuit and an output circuit, said input circuit being connected to said secondary winding of said input transformer, a second space discharge device, an interstage transformer having windings coupling said output circuit of the first mentioned space discharge device to said second space discharge device, said interstage transformer having leakage inductance of such value as to resonate with the distributed capacity of its windings and the capacitive impedance of said second space discharge device at a frequency near the upper end of said band thereby offering a low impedance to currents of said frequency in the output circuit of said first mentioned space discharge device and a higher impedance to currents therein of the lower frequencies in said band, whereby the input capacity and impedance of said first-mentioned space discharge device is controlled to give said input transformer a maximum voltage amplification for a given width of frequency band and a given distortion in the waves transmitted thereby.

13. A circuit for amplifying with substantially uniform efficiency and for offering a substantially uniform impedance to waves comprising a given band of frequencies, comprising an input transformer having an inductance which changes automatically with the frequency of the waves impressed thereon and a shunt resistance across its primary

winding, a space discharge device having a substantially capacitive input impedance fed thereby, an output circuit fed by said space discharge device, and means in said output circuit for making said capacitive impedance of said space discharge device remain substantially constant irrespective of the frequency of the waves supplied to said input transformer.

14. A circuit for amplifying with substantially uniform efficiency and for offering a substantially uniform impedance to waves comprising a given band of frequencies, comprising an input transformer having an inductance which decreases as the frequency of the waves supplied thereto increases, and a shunt resistance across its primary winding, a space discharge device having a substantially capacitive input impedance fed thereby, an output circuit fed by said space discharge device, and means in said output circuit for making the input capacity of said space discharge device decrease as the frequency of the waves supplied thereto increases.

15. A circuit in accordance with claim 12 and in which said means comprises a second transformer coupling said output circuit to a capacitive load circuit, said second transformer being such as to offer a low impedance to currents of the higher frequencies in said band and a higher impedance to currents of the lower frequencies in said band.

16. A circuit in accordance with claim 12 and in which said means comprises a second transformer comprising windings coupling said output circuit to a capacitive load circuit, and having leakage inductance of such value as to resonate with the distributed capacity of its windings and the capacitive impedance of said load circuit at a high frequency in said band and to cause said second transformer to produce in said output circuit a uniformly increasing impedance to currents therein of the lower frequencies in said band.

In witness whereof, I hereunto subscribe my name this 22nd day of September, A. D. 1927.

HORACE WHITTLE.
